TABULATING MACHINE

Joseph C. Mayorga and Albert A. La Pointe,
Hartford, Conn.

Application December 4, 1940, Serial No. 368,486

5 Claims. (Cl. 101—93)

The present invention relates to tabulating machines and more particularly to tabulating machines of the type which are used to record information denoted by the perforations formed in a perforated indicia bearing card.

The object of the present invention is to provide a tabulating machine of the above-indicated type of such a simplified nature that it will place such machines within the reach of small business enterprises. Heretofore, so far as applicant is aware, the tabulating machines for recording the information denoted by perforated cards have all been extremely complicated structures which were costly to manufacture and could generally be used profitably by enterprises having a tremendous amount of tabulating to be done. The machine incorporating the present invention is relatively small, and the entire operations thereof are accomplished through mechanical movements performed upon the operation of a single operating member, which member may either be operated manually or by a small power motor.

Another object of the present invention is to provide a tabulating machine of the above-indicated type which is extremely flexible in that the information recorded by the perforations in any column on the card may be transferred to any column on the sheet upon which the information is to be recorded. Not only can the above be accomplished, but the adjustment whereby it can be accomplished can be carried out by the user of the machine, and thus the machine can be quickly and readily interchanged to obtain a desired recording.

Other objects will be in part obvious and in part pointed out more in detail hereinafter.

The invention accordingly consists in the features of construction, combination of elements, and arrangement of parts which will be exemplified in the construction hereafter set forth and the scope of the application of which will be indicated in the appended claims.

In the accompanying drawings:

Figure 1 is a front view of a tabulating machine incorporating the invention herein;

Fig. 2 is a side view as seen from the right of Fig. 1;

Fig. 3 is a side view of the machine with the side plate of the casing removed;

Fig. 4 is a view similar to Fig. 3 from the opposite side of the machine;

Fig. 5 is a view with the front plate of the machine removed;

Fig. 6 is an exploded perspective view of de-

tails of construction showing means for interchanging the operation of the machine;

Fig. 7 is a view similar to Fig. 1, but showing a power operated machine; and

Fig. 8 is a view of a tabulating card of the type used in such tabulating machines.

Referring to the drawings, there is shown in Fig. 8 a perforated card 10 of the type which is used in conjunction with the tabulating machine 10 incorporating the invention herein. As indicated, the card is subdivided into six columns indicated by the letters A to F, inclusive, and each column further carries a vertically arranged numerical indicia from zero to nine. The cards

10 are originally fed through a punching machine, which machine provides a perforation 12 in each column from which information is to be transferred by the tabulating machine to a master sheet G on the machine. The master sheet G is provided with a plurality of columns corresponding in number to those on the card, whereby the information on a plurality of cards may be tabulated on a single sheet to make a single record thereof.

25 In order to effect this transfer, the tabulating machine shown herein comprises a rectangular casing 14 having front and rear walls 16 and 18 and side walls 20 and 22. The casing may be supported on a suitable base 24 and secured thereon

30 by angle plates 26 and the top of the casing closed by any suitable cover 28. The front and rear walls 16 and 18 are provided on their inner surfaces with opposed vertically extending guideways 30 in which there is slidably mounted a

35 card carrier 32. The card carrier comprises a relatively thin rectangular plate provided with six columns of perforations 34, each column having ten perforations corresponding to the numerical indicia on the perforated card 10,

40 whereby when a card is positioned on the card carrier a perforation punched in any column will align with the corresponding perforation on the card carrier.

In the machine illustrated, the cards 10 are 45 automatically fed into the machine to position same onto a card carrier 32. To accomplish this, there is mounted on the exterior of the front plate 16 a card support 35 (see Figs. 1 and 2) comprising a side plate 36 and a bottom plate 38. Ex-

50 tends vertically from the bottom plate 38 is a stop member 40, and intermediate of the member 40 and plate 36 there is a plunger 42 which is normally urged by a spring 44 towards the front plate 36 to always maintain one of the cards 10 55 against the plate.

As best seen in Fig. 1, the plate 36 has a channel 46 cut therein for receiving a feed bar 48 which extends transversely through the machine and lies in a plane rearwardly of carrier 32. The outer end of the feed bar is provided with a small projecting finger 50 adapted to engage the outer edge of one of the cards and, upon transverse movement of the feed bar, to carry the card inwardly and position it on the carrier. To allow the card to be fed inwardly, the carrier (see Fig. 4) has cut therein a transversely extending slot 52 which, when the carrier is in its lowermost position, is in alignment with the feed bar finger 50, and thus upon transverse movement the feed bar will move until the finger engages the end wall of slot 52, at which point the card will be so aligned that the perforations therein align with the perforations in the carrier 32. To guide and maintain the card in this position, the carrier further carries top and bottom, transversely extending, L-shaped guide members 54 spaced the depth of the card and adapted to hold the card in position on the carrier after the latter is fed into the guides 54.

To obtain this card feeding, the feed bar 48 is provided with a pair of spaced stops 56 (see Fig. 4) having positioned therebetween the lower end of a lever 58, which lever is pivoted adjacent its upper end on a pivot 60 mounted on a cross bar 62 supported between the side plates 16 and 18. Intermediate of the pivot 60 and its lower end the lever 58 has pivotally connected thereto the inner end of a second lever 64, the outer end of which is pivotally connected to a vertically extending lever 66. The upper end of the lever 66 engages a cam 68 mounted on an operating shaft 70, and intermediate of its ends the lever 66 is pivoted on a bracket 72 carried by the side plates 18. The cam 68 is formed with a flat 74, and when the upper end of the lever 66 engages the flat 74, the feed bar operating means will be in the position indicated by the broken lines in Fig. 4, in which position the feed finger 50 is located to feed a card into the machine. Upon rotation of the shaft 70 and cam 68 (clockwise in Fig. 4), the upper end of lever 66 will be pivoted in a counterclockwise direction and, through the interconnecting linkage, will carry the feed bar inwardly to the position indicated in Fig. 4 and feed a card onto the carrier 32.

To assure proper cooperation of the interconnecting linkage between the cam 68 and the return of the feed bar 48, there is further provided a spring 76 interconnecting the lever 66 intermediate of bracket 72 and its lower end and the upper end of the lever 58. The spring 76 will, upon operation of the feed bar 48, be expanded and tend to pivot lever 66 clockwise (see Fig. 4) and lever 58 counterclockwise, returning the parts to feeding position upon the upper end of lever 66 aligning with cam flat 74. To eject a card, a slot 78 is cut in the side wall 18 in alignment with the carrier guides, whereby the feeding of any successive card will eject a preceding card.

Following the feeding of a card onto the carrier, the carrier is raised vertically to align the perforations therein with the lower ends of a plurality of sensing devices 80. Referring initially to the means for raising the carrier, there is pivotally mounted centrally of and just below the upper edge of the carrier the lower end of a lever 84, the upper end of which is connected to one arm of a bell crank lever 86 which is also pivotally mounted on the cross bar 62. The other arm of the lever 86 en-

gages the lower end of a lever 88 which is pivoted intermediate of its ends on a bracket 90 and has its upper end in engagement with a cam 92 also mounted on the operating shaft 70. The cam 92 is also provided with a flat 94 against which the upper end of the lever 88 rests when the carrier is in its lowermost position, whereas upon rotation of the cam 92, the upper end of lever 88 (see Fig. 3) is pivoted in a clockwise direction to actuate bell crank 86 and move the carrier 32 vertically.

To have a proper sequence of operation, the flat 94 on the cam 92 is offset angularly with reference to the flat 74 on the cam 68 so that the raising movement of the carrier does not start until the feed bar 48 has been moved inwardly through the extent of the carrier slot 52, whereupon the perforated card will be properly positioned on the carrier. Upon raising the carrier, the feed finger 50 enters a carrier slot 96 extending vertically downwardly from the horizontal slot 52, and the feed bar 48 is held inwardly thereby until the carrier is again in lowermost or feed position.

As previously indicated, upon the raising of the carrier 32 the uncovered perforations therein will come into alignment with the lower ends of the sensing devices 80; there being provided a number of sensing devices corresponding to the number of columns on the perforated card 10. Herein, for purposes of simplicity, only six devices have been shown; it being apparent that this number may be expanded to perform the operations for any particular set of conditions.

More particularly, each sensing device 80 is carried by and depends from a transversely arranged operator slide 98 provided on its opposite ends with rollers 100 which guide the slide in suitable vertical grooves 102 provided in guide members 104 secured to the side walls 20 and 22 of the casing. As best seen in Fig. 5, each sensing device lies in a plane forwardly of the carrier 32 and includes a connector rod depending from the slide 98 and extending through a suitable guide opening in a bracket 106 for properly guiding the rod and also forming a limit stop for engaging a pin 108 carried by the rod above the bracket. Pivotally mounted on the lower end of each connector rod 105 is a sensing finger 110, the lower end of which has a projection 111 turned inwardly towards the carrier 32 and normally spring pressed into engagement with the carrier by a leaf spring 112 secured to the face of the rod 105 and engaging the finger 110 below the pivot thereof. When the parts are in inoperative position, the fingers 110 will normally engage the face of the carrier above the perforations 34. However, upon the raising of the carrier the lower ends 111 of the fingers 110 will become aligned with one of the perforations, whereupon the spring 112 will force it into same, and, upon further raising of the carrier, the slide will be raised simultaneously therewith. As best seen in Fig. 5, upon the lowering of the carrier, when the stop pin 108 engages the bracket 106, the carrier will engage the cam surface 114 of the finger projection 111 and cam it out of the perforation.

Each operating slide 98 in turn operates a second operating slide 116, and to each of the slides 116 there is connected a tabulating device comprising a vertically extending bar 82. In the embodiment disclosed, each of these bars may be provided adjacent their upper ends with type indicia from zero to nine corresponding to the

indicia on the perforated card. The slides 116 correspond in structure to the slides 98 and are mounted in like manner in guide plates 118 supported in the front and rear walls 16 and 18. It will be noted, however, that although the slides 116 are arranged in a plane parallel to the slides 98, they are also arranged at right angles to the slides 98. Likewise, each slide is of such length that it underlies or overlies all of the other slides.

In order to operate the bars 82 upon the actuation of the remote sensing devices 80, the slides 116 and slides 98 are interconnected by any suitable readily removable interconnecting means 120. In the embodiment illustrated, the interconnecting means 120 comprises a rigid rod having its lower end receivable within a recess 122 provided in the slide 98 and its upper end in a recess 124 provided in the slide 116; the weight of the parts being sufficient to keep same in interlocking position.

As best seen in Fig. 6, each slide has a number of recesses 124 corresponding to the number of sensing devices 80 and bars 82, and as the slides are arranged at right angles to one another, it is possible to shift the rod 120 whereby any sensing device 80 may be connected to any selected bar 82. For example, the rod 120, which connects the slides designated as *a* and *b*, could be shifted to connect the slide *a* with the type bar carrier designated as *c*. In like manner, the interconnecting rod 120a could be shifted to connect the slide *d* with the slide *b*. With this arrangement, it is possible to connect any sensing device with any type bar, and thus if the columns on the master sheet G upon which the information is to be printed are not in the same sequence as the columns on the perforated card, the connections between the slides may be interchanged so that the information from the proper column on the perforated card will be printed in the proper column on the master sheet.

Reviewing the operation to this point, it will be seen that upon rotation of the shaft 70 by the operating handle 78, the feed bar 48 will initially operate to move a card into position on the carrier 32. When so positioned, the carrier will then be moved vertically until the projecting ends 111 of the sensing fingers align with the perforation in the card and carrier, whereupon the spring 112 will pivot the projection into such perforation. Thereafter the sensing devices will be moved to cause actuation of the slides 98, which slides in turn, through the rods 120, will cause simultaneous actuation of the slides 116 to move the bars 82. Obviously the indicia on the type bar will be raised an amount corresponding to the movement of the platen following the engagement of an operator and thus properly align same for printing onto the master sheet.

To obtain such printing, there is associated with the type bars a pressure roll 126 which is pivotally mounted on a pair of spaced arms 128. The arms 128 are in turn pivotally mounted on a rod 130 extending between the side plates 20 and 22. The arms 128 extend below the rod 130 and have their lower ends resting against the operating shaft 70 in which position the pressure roll 126 is out of contact with the type bars. To hold it in such position, there is provided a spring 132 mounted on the rod 130 and having one end extending across the arm 128 above the rod 130 (see Fig. 3).

To move the pressure roll 126 into contact with the type bars, there is mounted on the operating shaft a pair of spaced collars 134 each carrying

an inwardly and laterally projecting pin 136. The pins 136 are angularly arranged with relation to cams 88 and 92 so that they will not come into operation until the type bars have been raised to their proper printing position. Thereafter the pins 136 will engage the lower ends of the arms 128 to force the pressure roll 126 against the type bars to print the indicia onto the master sheet.

10 To advance the master sheet, the pressure roll 126 also has associated therewith a ratchet 138 engaged by a free end of spring finger 140 mounted on the top plate of the casing 14. Upon the movement of the pressure roll 126 into printing position, the ratchet will move across the finger 140; whereas upon the reverse movement, the finger will engage one of the teeth of the ratchet 138 and rotate the roller. The master sheet may be held in contact with the surface 15 roll in any suitable way, such as by the clamps commonly used on the ordinary typewriter, and as these are well known no showing or description need be made thereof. The master roll may also be provided with a manually operable handle 142 for rotating it to clear the master sheet.

20 It will thus be seen that by the operation of the single shaft 70 a perforated card is fed into the machine, and thereafter mechanism is actuated to properly set the various type bars, and, 25 following this, the master roll 126 is brought into pressure contact with the type bars to register onto the master sheet the information designated by the perforations on the perforated card. Due to the arrangements of the cams, a proper 30 sequence of operation is assured, and as the feed bar is locked upon raising of the carrier, a second card cannot be fed until all the parts have returned to feeding position. The operation of shaft 70 may be accomplished manually by providing on the extending end thereof an operating 35 handle 78 (see Fig. 1) or a pulley 152 belt-driven from a small motor 154 (see Fig. 7).

40 As all the operations are carried out by the operation of the single operating shaft, it is apparent that once a plurality of cards 10 are mounted onto the card holder 35 they will thereafter be automatically fed into the machine and ejected therefrom and the information thereon mechanically transferred to a master sheet. If 45 for any reason it is necessary to readjust the mechanism to align any particular type bar with any particular sensing device, this is readily accomplished by simply taking off one of the side plates and shifting the interconnecting rods 120 50 to proper position; it being obvious that anyone could readily make such adjustments to meet the required conditions.

55 As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

60 It is also to be understood that the language used in the following claims is intended to cover all of the generic and specific features of the invention herein described and all statements of 65 the scope of the invention which, as a matter of language, might be said to fall therebetween.

70 We claim as our invention:

75 1. In a tabulating machine of the character described, a plurality of vertically arranged tabulating devices, a transversely arranged slide for

each tabulating device, a plurality of vertically arranged sensing devices, a transversely arranged slide for each sensing device, the slides for said sensing devices being arranged at right angles to the slides for said tabulating devices and in a plane parallel thereto, and interchangeable rigid connecting means interconnecting each tabulating device slide with a selected sensing device slide.

2. In a tabulating machine of the character described, a plurality of tabulating devices each having a slide, said slides being arranged in generally parallel side by side relation, a plurality of sensing devices each having a slide, said last mentioned slides being arranged in generally parallel side by side relation in a plane parallel to the plane of said first mentioned slides, the slides of one set being arranged transversely to those of the other set whereby the slides of the respective sets cross each other, means for supporting said slides for movement generally at right angles to the planes in which they extend, and interchangeable rigid connecting means for selectively interconnecting the slides of the first set with those of the second set.

3. In a tabulating machine of the character described, a plurality of tabulating devices each having a slide, said slides being arranged in generally parallel side by said relation, a plurality of sensing devices each having a slide, said last mentioned slides being arranged in generally parallel side by side relation in a plane parallel to the plane of said first mentioned slides, the slides of one set being arranged transversely to those of the other set whereby the slides of the respective sets cross each other, means for guiding said slides for movement generally at right angles to the planes in which they are arranged, each of said slides having on its face opposing the slides of the other set recesses spaced apart in accordance with the spacing apart of the slides

of said other set, and removable interchangeable rods respectively connecting the slides of one set with those of the other and having their ends seated in opposed recesses.

5. 4. In a tabulating machine of the character described, a plurality of movable sensing devices, a plurality of vertically movable slides respectively associated with said sensing devices and adapted to be moved vertically thereby, said slides extending transversely to the direction of their movement and being arranged in generally side by side parallel relation, a plurality of tabulating devices, a plurality of vertically movable slides respectively associated with said tabulating devices and disposed above said first set of slides, said second set of slides being arranged in generally side by side relation and extending crosswise of the slides of the first set, and interchangeable rigid connecting means for selectively interconnecting the slides of the first set with those of the second set.

5. In a tabulating machine of the character described, a plurality of tabulating devices, a set of slides respectively associated with said tabulating devices so as to actuate the same, said slides being arranged in generally side by side parallel relation and being independently movable at right angles to the directions in which they extend and are spaced apart, a movable sensing device, a slide actuated by movement of said sensing device, said last mentioned slide being disposed transversely of said first mentioned slides in a plane parallel to the plane of the first mentioned slides whereby said slide actuated by the sensing device is arranged crosswise of said first mentioned slides, and a detachably mounted rigid connecting member for selectively connecting said slide actuated by the sensing device with said first mentioned slides.

JOSEPH C. MAYORGA.
